UNITED STATES PATENT OFFICE.

JOSEPH FOSSEE, OF CRAWFORDSVILLE, INDIANA.

HINGE.

No. 793,405.

Specification of Letters Patent.

Patented Aug. 29, 1905.

Application filed June 22, 1904. Serial No. 213,664.

To all whom it may concern:

Be it known that I, JOSEPH FOSSEE, a citizen of the United States, residing at Crawfordsville, in the county of Montgomery and 5 State of Indiana, have invented certain new and useful Improvements in Hinges; and I do hereby declare the following to be a full, clear, and exact description of the invention, such as will enable others skilled in the art to 10 which it appertains to make and use the same.

My invention relates to hinges.

It has for its object to retain the cover on the receptacle at all times, lock it in position upon the receptacle, and permit said cover to 15 be swung around and suspended at the side of said receptacle.

To this end the invention consists of a projecting arm adapted to be secured to the body of the receptacle and having a lug with an 20 enlarged head adapted to confine a plate portion adapted to be fastened to the cover and having a slot partly straight and partly rounded out to permit it to swing laterally and to pass over the end of said arm, so that 25 the cover can be hung from said arm at the side of the receptacle, but not allowing said slot to pass over the head of the lug on said arm, the straight portion of said slot adapted to fit around said lug and below the head 30 thereof to lock the cover against upward movement with relation to the body of the receptacle. If the lug is made angular in cross-section, as shown in the drawings, and the straight portion of the slot is made to 35 fit closely around said lug, the cover will be locked against lateral movement.

In the accompanying drawings, illustrating the preferred embodiment of my invention, Figure 1 is a broken elevation of my hinge 40 attached to portions of the body and cover of a cylindric receptacle, the hinge being in a locked position. Fig. 2 is a plan view thereof. Fig. 3 is a broken sectional view on the line $\alpha\alpha$ of Fig. 2. Fig. 4 is a sectional view of 45 the plate, taken on the line $\gamma\gamma$ of Fig. 2. Fig. 5 is an elevation looking inward toward the end of the arm, showing the plate connected to the cover turned and in the act of passing over the end of said arm; and Fig. 6 50 is an elevation taken from the same point as Fig. 1, showing the cover hung from the arm at the side of the receptacle.

Referring more particularly to the drawings, the hinge comprises a bracket 2, having 55 an outwardly-extending arm 1 and an inwardly-extending lug 3, adapted to be seated

upon a ledge of the receptacle 4. At the end of the arm is an upstanding lug 5, having an enlarged head 6. Said lug is preferably angular in cross-section, and it is attached to the arm 60 by screw or other suitable connection. The outer end of the arm is enlarged and preferably rounded. Above said arm, adapted to work back and forth on said lug and confined to said arm by the head on said lug, the plate 7, connected at its inner end to the cover 8, is provided with a slot 9 in its outer portion. Said slot is partially straight at its outer extremity and rounded out, as at 10, at its inner extremity. The walls of the rounded-out portion 70 are inclined downwardly and outwardly, as at 11, to permit the opening to pass over the end of the arm to drop the cover at the side of the receptacle, but leaving the opening at the upper surface of the plate so small 75 that it will not pass over the head of the lug. The arm is of such width, at least at one point, as at 12, to permit of the passage of the restricted portion of the slot therearound.

In the positions shown in Figs. 1 and 2 the 80 cover is in place on the receptacle and is locked against upward or lateral movement. To remove the cover, it is pushed back until the enlarged portion of the slot in the plate is around the lug. Said plate will then be 85 free to revolve around said lug and the cover turned to either side to provide access to the receptacle. To drop the cover to the side of the receptacle, the enlarged portion of the slot is slipped over the end of the arm, as shown 90 in Fig. 5, at a sidewise position, and said cover is turned so that it is suspended at the point 12 of said arm by the extremity of the straight portion of the slot. To place the cover on the receptacle, this operation is reversed. 95

If desired, the lug may be made round, so that the plate and cover may revolve freely around it, but still locking said cover against upward movement.

I am aware that other changes may also be 100 made in my invention without departing from the spirit or sacrificing the advantages thereof. I therefore reserve the right to make such changes as fairly fall within the scope of my invention.

Having thus described my invention, what I claim as new, and desire to secure by Letters Patent, is—

1. A hinge comprising a bracket having a 110 projecting arm provided with a lug having an enlarged head, and a plate portion having a slot and confined to said arm by the head of

said lug, a portion of said slot being adapted to fit closely around said lug and also having a portion wider than said lug but narrower than the head of said lug.

5. 2. A hinge comprising a bracket having a projecting arm provided with a lug having an enlarged head, and a plate portion having a slot partially straight and partially rounded out, the straight portion of said slot adapted to fit closely around said lug, said plate confined to said arm by the head of said lug. 30

15. 3. A hinge comprising a bracket having a projecting arm provided with a lug angular in cross-section, said lug having an enlarged head, and a plate portion having a slot partially straight and partially rounded out, the straight portion of said slot adapted to fit closely around said lug and lock said plate against lateral movement, said plate confined 35

20. to said arm by the head of said lug.

4. A hinge comprising a bracket having a projecting arm provided with a lug having an enlarged head, and a plate portion having a slot partially straight and partially rounded 40

25. out, the straight portion of said slot adapted

to fit closely around said lugs and the walls of the enlarged portion of said slot inclined outwardly and downwardly whereby it is adapted to pass over the end of the arm, said plate confined to said arm by the head of said lug. 30

5. A hinge comprising a bracket having a projecting arm provided with a lug having an enlarged head, said arm having an intermediate laterally-reduced portion, and a plate portion having a slot partially straight and partially rounded out, the straight portion of said slot adapted to fit closely around said lug, and the enlarged portion of said slot inclined outwardly and downwardly whereby it is adapted to pass over the end of the arm so 40

that the plate portion may be suspended by the extremity of the smaller portion of the slot engaging the intermediate laterally-reduced portion of said arm. 35

In testimony whereof I affix my signature in 45 presence of two witnesses.

JOSEPH FOSSEE.
